DESIGN FOR A STREET SIGN BOARD

Lloyd E. Best, Kansas City, Mo.

Application November 25, 1933, Serial No. 49,864

Term of patent 7 years

To all whom it may concern:

Be it known that I, Lloyd E. Best, a citizen of the United States, residing at Kansas City, in the county of Jackson and State of Missouri, have invented a new, original, and ornamental Design for a Street Sign Board, of which the following is a specification, reference being had to the accompanying drawing, forming a part thereof.

Fig. 1 is a perspective view of a street sign board made in accordance with my new design, the lettering thereon being merely illustrative, and

Fig. 2 is a vertical sectional view on the line 2—2 of Figure 1.

The sign board has a generally rectangular

main portion having a smaller substantially central generally rectangular supplemental portion extending from one edge thereof, said portions merging in a smooth curve. The narrow edge faces of the sign board are provided with a bead running lengthwise substantially centrally thereof.

I claim:

The ornamental design for a street sign board substantially as shown and described.

In testimony whereof I hereunto subscribe my name this 22nd day of June, 1933.

LLOYD E. BEST.
